UNITED STATES PATENT OFFICE.

ELWOOD SCOTT, OF MARION, INDIANA, ASSIGNOR OF ONE-HALF TO ROBERT RIDGWAY, OF AMBOY, INDIANA.

COOKING STOVE OR RANGE.

No. 881,962.

Specification of Letters Patent. Patented March 17, 1908.

Application filed February 25, 1907. Serial No. 359,133.

To all whom it may concern:

Be it known that I, ELWOOD SCOTT, a citizen of the United States, residing in the city of Marion, in the county of Grant and 5 State of Indiana, have invented certain new and useful Improvements in Cooking Stoves or Ranges; and I do hereby declare the following to be a full, clear, and exact description of the invention, being such as will enable others skilled in the art to which it 10 pertains to make and use the same.

My present invention relates, generally speaking, to cooking stoves or ranges, and particularly to means for heating the oven 15 and maintaining it at a uniform degree of temperature with a minimum amount of fuel, in which heat may be concentrated where desired without abnormally heating other parts of the stove or range, and with a 20 minimum of radiation into the room in which the stove or range is located.

As above intimated the invention has reference more particularly to the means for heating oven, the object being to provide an 25 oven having a maximum of heating surface therein with dimensions, and also to provide means for directing the heat in a plurality of routes, in order to meet various conditions and requirements.

30 The preferred manner by which I accomplish the objects of my invention is shown most clearly in the accompanying two sheets of drawings, in which—

Figure 1 shows in perspective a portion of 35 stove or range, partly in section, with the top removed in order to give an introspective view of some of the essentials of this invention. Fig. 2 is a top plan view of the same. Fig. 3 is a longitudinal sectional 40 view as taken on the line $x-x$ of Fig. 2. And Fig. 4 is a detail sectional view as taken on the line $z-z$ of Fig. 2.

Similar indicia denote like parts throughout the several views.

45 The details of the invention are substantially as follows:

The letter A designates the oven space. B designates the fuel and combustion chamber. The letter C denotes the top of the 50 stove, and the letter D denotes the bottom of the stove. The letter E denotes the base, the letter F the front wall of the oven, the letter G denotes the rear wall of the oven, and H denotes the top-plate of the oven. 55 And the letter I denotes the escape pipe.

All of said parts are of common construction, and may be variously changed in order to meet certain conditions and requirements.

The essential requisites of my invention are the flues, which are divided into three sets: the front vertical flues 1, the horizontal bottom flues 2, and the rear vertical flues 3. Said flues are, preferably, trapezium shaped in cross section. The superficial extent of said flues, together with the top plate 60 H, form the heating surface of the oven. The upper ends of the flues 1 are located on a level with the top-plate H and with the upper edge of the back of the combustion chamber B, from which point they extend 65 downward along the front wall F, with their lower ends all opening into a common chamber 4, which latter extends laterally across the lower portion of the stove, its bottom being on a line with the bottom D. 70

The bottom flues 2 have their forward ends opening into the rear wall of the chamber 4, from which they extend to the rear, where each one is joined to one of the flues 3, which latter extend upward along the rear 75 wall G with their upper ends on a level with the top-plate H. It of course should be understood that at their upper ends the flues 1 and 3 are fitted in a horizontal plate, as the plate H, the interiors of said flues only 80 being exposed at their upper ends, substantially as indicated in the drawings. 85

In practice the front wall F may be integral with the flues 1, and the bottom D may be integral with the flues 2, and likewise the wall G may be integral with the flues 3, or said flues may each be separate 90 from each other and from said parts F, D and G.

The numeral 5 denotes a partition extending 95 up from the plate H to the top C of the stove, same being located immediately forward of the upper ends of the flues 3. Said partition should have three oblong apertures therethrough each to be closed by a damper, 100 although the center aperture may be omitted if desired. If employed, then the center aperture is adapted to be closed by a damper 6, which is adapted to be operated from the side of the stove as shown. The two side 105 apertures of said partition are adapted to be closed by a separate damper, 7 and 8, which swing horizontally and are operable from the top of the stove as shown. Said dampers 7 and 8 are pivoted at the parts which divide 110

said apertures in the partition 5, and they are adapted to swing back at right angles to said partition in order to connect with the rear wall G, thereby dividing the space which 5 is formed by the partition 5, the upper ends of the flues 3, the rear wall G, and the top of the stove C, into three parts, as is indicated in Fig. 1. The escape pipe I leads from the center portion of the chamber just described.

10 Located immediately in the rear of the upper end of the flues 1 is a damper 9, operable from the side of the stove. Said damper 9 is adapted to close the space between the top-plate H and the top C of the stove, or to 15 be turned back, all substantially as indicated.

15 The operation of my stove is substantially as follows: If a fire be maintained in the fuel chamber it is evident that various movements of the draft may be directed therefrom 20 by means of said dampers.—Suppose for instance, (a) that the damper 9 be turned back, and the damper 6 be turned forward, it is evident that the draft will pass back over the plate H, through the center aperture of the 25 partition 5, and then up the pipe I, thus making a direct draft, as is usually required in starting a fire. (b) Now if the damper 9 be closed (preferably at this operation the 30 dampers 6, 7 and 8 should be positioned to close all of the apertures in the partition 5), that the draft from the fuel chamber will be directed downward through the flues 1, into the chamber 4, thence through the flues 2, up through the flues 3, and into the space 35 back of the partition 5, and from there it may escape up the pipe I. (c) If the dampers 7 and 8 be turned back, as in Fig. 1, the damper 6 closed, and the damper 9 opened, another movement of the draft will be accomplished, 40 that is to say,—the draft will pass back over the plate H, through the side apertures of the partition 5, and by reason of the position of the dampers 7 and 8 the draft will pass down through the four outside flues 3, for- 45 ward through the four outside flues 2, then into the chamber 4 where it will turn and pass to the rear through the four center flues 2, then up the four center flues 3, into the space between the partition 5, the two dampers 50 7 and 8, and the rear wall G, and the top C, from whence it will be free to escape through the pipe I.

55 As explanatory of the terms used in the following claims, it is pointed out that there may be regarded as being two sets of dampers below the stove top, the damper 6 comprising one set and the dampers 7 and 8 the other. It will be seen that, when the damper 6 is closed, it partially cuts off communica- 60 tion between the space between the oven and stove top on the one hand and the top of the flues 3 on the other, and that, when the dampers 7, 8 occupy positions in the same plane with damper 6, they coöperate with 65 the latter to cut off such communication en-

tirely, while, when positioned as in Fig. 1, and the damper 6 closed, they coöperate therewith to cut off communication between said space on the one hand and the smoke outlet and a portion of the uptake flues on the other, and to place said space in communication with the remainder of the uptake flues. 70

75 From the above it is evident that an oven constructed as described will have approximately three times more heating surface than that of an ordinary oven of the same dimensions; also that the oven just described may be heated very quickly and maintained at a more uniform temperature with less fuel than 80 has heretofore been attained.

85 Having now fully shown and described my invention and the best manner for its construction to me known at this time, I desire to have it distinctly understood that various changes and modifications may be made in the details thereof without in any manner departing from the spirit of the invention or of sacrificing any of the many 90 advantages.

95 What I claim and desire to secure by Letters Patent of the United States, is—

1. The combination in a cooking stove having a firebox, an outlet for products of combustion, and an oven spaced below the top of the stove, of a downtake for products of combustion leading from the firebox down one side of the oven, intercommunicating horizontal flues underlying the oven and having communication at one end with said 100 downtake, uptake flues leading from the other ends of said horizontal flues along the opposite side of the oven and spaced at their upper open ends below the stove top, and two sets of dampers below the stove top, 105 one set being adapted when closed to cut off partially communication between the space between the oven and stove top on the one hand and the outlet and the tops of said uptake flues on the other hand, and the other 110 set being pivoted on vertical axes to swing laterally, being adapted in one position to coöperate with the first set to cut off such communication completely and in another position to coöperate therewith to cut off 115 communication between said space on the one hand and the outlet and a portion of the uptake flues on the other hand and to place said space in communication with the tops of the remainder of the uptake flues. 120

2. The combination in a cooking stove having a firebox, an outlet for products of combustion, and an oven between the firebox and outlet and spaced below the top of the stove, of a downtake leading from the firebox along the front of the oven, intercommunicating horizontal flues leading from the bottom of said downtake beneath the oven, uptake flues leading from the rear ends of said horizontal flues along the rear of the 125 130

oven and spaced at their open upper ends below the stove top, a damper adapted when closed to cut off all passage of products of combustion from the firebox rearward 5 through the space above the oven, and two other sets of dampers below the stove top and in rear of the other damper, one set being adapted when closed to cut off partially communication between said space on the 10 one hand and the outlet and the tops of said uptake flues on the other hand, and the other set being pivoted on vertical axes to swing laterally, being adapted in one position to coöperate with the first set to cut off such 15 communication completely and in another position to coöperate therewith to cut off such communication between said space on the one hand and a portion of the uptake flues on the other hand, said portion being in communication with the outlet, and to place said 20 space in communication with the tops of the remainder of the uptake flues.

3. The combination in a cooking stove having a firebox, an outlet for products of combustion, and an oven between the firebox and outlet and spaced below the top of the stove, of a downtake leading from the fire box along the front of the oven, inter-communicating horizontal flues leading from

the bottom of the downtake beneath the 30 oven, uptake flues leading from the rear ends of said horizontal flues along the rear of the oven and spaced at their upper open ends below the stove top, said ends being in communication with the outlet, an upright plate 35 extending across the space between the oven and stove top in advance of the tops of said uptake flues and having a central and two lateral damper openings, a damper controlling the central opening, and two other 40 dampers pivoted at their inner ends on vertical axes and adapted in one position to close said lateral openings and when swung rearward to inclose with said other damper and the frame of the stove a chamber 45 communicating only with the outlet and the tops of the central uptake flues, the tops of the lateral uptake flues being then in communication with the space between the oven and stove top.

In testimony whereof I have hereunto signed my name to this specification in the presence of two subscribing witnesses.

ELWOOD SCOTT.
